Primary Examiner — Barbara Fox(74) *Attorney, Agent, or Firm* — Baker & Hostetler LLP(57) **CLAIM**

We claim the ornamental design for a display screen with a graphical user interface, as shown and described.

DESCRIPTION

This disclosure contains material that is trademarked and copyrighted. The Applicants do not object to reproduction of the patent document as it appears in United States Patent and Trademark records, but otherwise reserve all other copyright and trademark rights.

The FIGURE is a front view of a display screen with a graphical user interface of the present invention.

The broken lines shown in the drawings are for the purpose of illustrating a display screen with a graphical user interface and form no part of the claimed design.

ONLINE REGISTRATION: GLENVIEW

STEP 1: **Search**

3. Lessons or camp

Would you like to find a new lesson, or camp?

Lessons

2. Search

How would you like to search for classes in GLENVIEW?

Use SWIMMY'S RECOMMENDED technology to find classes for all my children at this camp day and time.

Or, find classes using a customized search:

None

STEP 2: **Find my class**

STEP 3: **Confirmation**

3. Search Results

Select the start date from the list below: (Classes will automatically appear below)

MONDAY	TUESDAY	WEDNESDAY	THURSDAY	FRIDAY	SATURDAY	SUNDAY
6:00 AM 6:30 AM 6:30 AM	6:00 AM 6:30 AM	6:00 AM 6:30 AM	6:25 AM 6:30 AM 6:30 AM 6:30 AM	6:00 AM 6:30 AM	8:00 AM	8:00 AM

Hint: You may add multiple classes by selecting multiple start days & times

4. Confirm

Confirm your new class details and press submit:

Swimmer	Level	Price
NEW LESSON Name: 00-00-0000 Starts: 02/01/2012 8:00AM	test	1 Day/ 1 \$0
